CLAIM

I claim the ornamental design for a bottle, as shown and described.

DESCRIPTION

FIG. 1 is a perspective view of a bottle showing my new design;

FIG. 2 is a front elevational view;

FIG. 3 is a top view; and,

FIG. 4 is a bottom view.

The broken line showing in FIGS. 1, 2, & 4 is for illustrative purposes only and forms no part of the claimed design.
